UNITED STATES PATENT OFFICE.

CHARLES W. BOND, OF LA GRANDE, OREGON.

COMBINATION MILKING STOOL AND PAIL HOLDER.

Application filed June 20, 1928. Serial No. 286,845.

This invention relates to a combination milking stool and pail holder.

The main object is to provide an efficient and sturdy device which will protect the milk from foreign matter such as dirt, dust or the like, and which will have a milk receiving element and means for readily adjusting the milk receiving element, both vertically and horizontally.

10 Another object is to provide a device of the above named character which will be simple in construction and readily dismantled for cleaning and the like.

With these and other objects in view, the invention resides in the novel construction and arrangement of the parts as hereinafter set forth and claimed.

In the drawing

Figure 1 is a side view, partly broken away, 20 of my invention.

Figure 2 is a plan view thereof.

Figure 3 is a detail of the retaining ratchet and its associated elements.

In practicing my invention I provide a pail holder 1 of any suitable material and shape being here shown as circular and having the flared walls or sides 2 and adapted to receive the conventional milk pail 3. A top or closure 4 is attached by a hinge 5 to the side 2 and at a 25 diametrically opposite point a conventional spring catch 6 is secured to releasably retain the top 4 in the closed position. 7 is a handle affixed to a medial point of the top by means of which the pail holder and associated elements 30 may be carried from place to place. It is obvious that a conventional bail (not shown) 35 may readily be used in lieu of the handle 7 if desired.

Secured to the pail holder 1 near its top 40 and to one side of the spring catch 6 is a bracket 8 having an aperture 21 in which is rotatably and slidably mounted an elongated circular post 9 and a set screw or wing bolt 10 in the bracket 8 permits the post 9 to be secured in any adjusted position. A swinging 45 arm element or assembly 11 of the conventional parallel motion type is provided, the same comprising the spaced parallel levers 12 and 13 pivoted at one end in the post 9 at 14 and being pivotally connected at 16 at their 50 outer ends to a cross piece 15. Extended out-

wardly from the cross piece 15 is a socket element 17 having a tapered bore or socket 18. A funnel 19 is provided with a tapering plug or finger 20 on its side which is adapted to 55 seat within and frictionally engage the socket 18 so that the said funnel will be releasably retained in position upon the arm 11.

From the foregoing it will be understood that the arm element or assembly 11 may be 60 swung up or down as desired and the funnel 19 will at all times remain in the vertical position. To retain the arm assembly 11 in any adjusted position I provide the arcuate ratchet arm 22 secured at its lower end to the 65 post 9 at 23 and having the ratchet teeth 33 upon its inner margin as shown.

Spaced brackets 24 and 25 are secured upon the lever 12 and a pawl 26 is slidably mounted therein being spring set by coil spring 27 70 braced between the bracket 24 and a collar 28 which normally holds the said pawl in engagement with the ratchet teeth. A finger piece 29 is provided to operate the pawl and it will be understood that the arm assembly 11 75 may be secured in any adjusted position by this means.

The funnel 19 is provided with an elbow 30 over the end of which may be placed a flexible tube or hose 31 made of rubber or the like, 80 which extends within the pail holder 1 through a suitable aperture in the side thereof, so that milk discharged into the funnel 19 will flow into the pail 3. The tube 31 is supported by small loops or hangers 32 secured to the 85 lever 13 and these loops are preferably made of spring material to allow the tube 31 to be readily removed therefrom for cleaning.

The use of the device will be obvious from the foregoing and it will be understood that 90 the funnel 19 may be adjusted vertically by raising the entire supporting assembly mounted upon the post 9 in the bracket 8 and also by swinging the arm assembly 11 up or down. The funnel may be adjusted horizontally by 95 turning the post 9 in the bracket 8.

While I have herein set forth a preferred embodiment of my invention it is understood that I may vary from the same in minor details within the scope of the appended claim. 100

I claim:

In a device of the character described, a

pail holder, a post rotatably and slidably mounted for vertical movement on the pail holder, a parallel motion frame pivoted vertically at one end to the post for vertical movement, an arcuate ratchet arm disposed vertically across the parallel motion frame and having its lower end secured to the post, a

pawl slidably mounted upon the parallel motion frame and adapted to engage the said ratchet arm to lock the frame at any set position. 10

In testimony whereof I affix my signature.

CHARLES W. BOND.
